UNITED STATES PATENT OFFICE.

ALBERT EDWARD HODDER, OF LONDON, ENGLAND, ASSIGNOR OF ONE-HALF TO JOHN BINGLEY GARLAND LESTER, OF SAME PLACE.

CARBURETER.

SPECIFICATION forming part of Letters Patent No. 659,476, dated October 9, 1900.

Application filed August 19, 1899. Serial No. 727,826. (No model.)

To all whom it may concern:

Be it known that I, ALBERT EDWARD HODDER, a subject of the Queen of England, residing at London, England, have invented certain new and useful Improvements in Carbureters, (for which I have made application for Letters Patent in Great Britain under No. 10,439, dated May 17, 1899,) of which the following is a specification.

10 This invention relates to the manufacture and distribution of gas for lighting and heating and comprises a power-station, from which air is forced along mains through the district to be illuminated. From these mains branch 15 pipes are led to the various installations in the system. A generator is provided at each installation and comprises two or more concentric annular carbureting-chambers, each connected to the air-supply main by means 20 of a conduit provided with a cock in order to independently regulate the amount of air passing to each chamber. Hydrocarbons of different specific gravities are employed separate from each other, each hydrocarbon being 25 allotted its own chamber. By the separation of the hydrocarbons and by the arrangement of an independent air-supply to each the proportion of carbureted air obtainable from each chamber can be adjusted so that the 30 gas resulting from the mixture of these carbureted streams may have the quality or richness desired. An air-relief valve is provided upon the air-main adjacent to each generator in order that the pressure therein may 35 not exceed a given maximum value.

In the accompanying drawings, Figure 1 is a vertical section of a gas-generator constructed according to this invention, showing the various pipe connections hereinafter referred to.

40 Fig. 2 is a plan of the gas-generator, partly in section, on the line 2 2 of Fig. 1.

Like letters indicate like parts throughout the drawings.

The generator comprises a cylindrical vessel A, which is divided by means of two concentric cylindrical partitions B and C into two outer annular chambers A' B' and an inner cylindrical one C'. This latter chamber C' is provided with a perforated false bottom

C², situated a short distance above the common bottom A² of the three chambers, while the two outer chambers A' B' are each fitted with spiral blades or vanes A³ B³, so arranged that air delivered into the bottom of either chamber will be forced to travel several times around it in a helical path through the liquid contained therein as it rises toward the upper end. The chamber C' is filled with naphthalene, preferably purified naphthalene, resting on the perforated false bottom C². The two outer annular chambers A' B' contain, respectively, a heavy hydrocarbon (such as petroleum having a flash-point at or about 120° Fahrenheit) and a light petroleum ether or benzine. The various chambers are filled through orifices provided at their upper ends and capable of being hermetically sealed by means of plugs A⁴ B⁴ C³.

Compressed air is supplied from a central pumping-station through the main D and led 70 through the branch pipes D' D² to the bottom of the chambers A' B', respectively.

The pipes D' D² are continued up through the bottom A² of the generator, as shown at D³ and D⁴. Their ends D³ and D⁴ are received 75 in inverted stopped tubes E, which are perforated at their lower ends, as shown at E', the liquid in the space between these concentric tubes forming a liquid seal. Any other form of liquid seal may be used, however, or an ordinary non-return valve may be provided in the pipes D' D².

The tops of the chambers A' B' are connected to the top of the chamber C' by means of the pipes A⁵ B⁴, and from the bottom of the latter chamber a pipe C⁴ leads to the burners. One or both of the pipes A⁵ B⁴ may be provided with a cock.

A loaded relief-valve F of any convenient construction is provided on the air-main D 90 adjacent to each generator. The maximum pressure of air in the generator and of gas in the system may be regulated by varying the pressure on the valve F.

Hand-controlled valves G H are provided 95 in the pipes D' D², and by means of these cocks the amount of air passing through the carbureting-chambers A' B' may be inde-

pendently controlled so as to regulate the richness of the resulting gas, as previously described.

In an apparatus such as described there will be two independent streams of air, one passing through the chamber A' and the other through the chamber B'. Thence being saturated with the vapor of the liquids contained in the two chambers A' B' the two streams unite in the central chamber C' and become further enriched in passing through the purified naphthalene contained therein. From the chamber C' the gas is led direct to the burners (which are fitted with incandescent mantles if the gas is to be employed for the production of light) by means of the pipe C⁴.

Having now particularly described and ascertained the nature of my said invention and in what manner the same is to be performed, I declare that what I claim is—

1. In an apparatus of the character described, the combination with a series of carbureting-chambers arranged one within the other, of a series of spirally-arranged vanes within each of said chambers, an air-inlet pipe leading into each chamber below the vanes therein, and a carbureted-air-outlet pipe leading from each chamber above the vanes, as and for the purpose set forth.
2. In an apparatus of the character described, the combination with a carbureting-chamber, of a series of spirally-arranged vanes therein, an air-inlet pipe leading into said chamber below the vanes, a carbureted-air-outlet pipe leading from said chamber

above the vanes, and a chamber adapted to contain an enriching agent into which the said outlet-pipe leads.

3. In an apparatus of the character described, the combination with a series of carbureting-chambers arranged one within the other, of a series of spirally-arranged vanes within each of said chambers, an air-inlet pipe leading into each chamber below the vanes therein, a carbureted-air-outlet pipe leading from each chamber above the vanes, and a chamber adapted to contain an enriching agent arranged within the innermost carbureting-chamber and into which the said outlet-pipes lead. 50

4. In an apparatus of the character described, the combination with a series of annular carbureting-chambers arranged one within the other and spirally-arranged vanes in each chamber, of a central chamber, a perforated bottom therefor, an air-inlet pipe leading into each carbureting-chamber below the vanes therein, a carbureted-air-outlet pipe leading from each carbureting-chamber above the vanes and into the central chamber, and an outlet-pipe leading from the central chamber below the perforated bottom thereof. 55

In testimony whereof I have hereto set my hand in the presence of the two subscribing witnesses.

ALBERT EDWARD HODDER.
